WILHELM MOSER, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

SYSTEM FOR KEYING TRANSMITTERS

Application filed January 13, 1926, Serial No. 80,926, and in Germany March 7, 1925.

The keying of tube transmitters for short waves is attended with a number of difficulties which manifest themselves upon the reception of such waves. In beat reception, for example, a far higher wave constancy is necessary than when working with longer waves. For instance, if a 30-meter wave undergoes a variation of only $\frac{1}{10}$ th of one percent this means that the frequency (10^7 per second) will change by 10,000 oscillations per second. The beat tone is subject to fluctuation by an equal amount, with the result that proper sound-reading reception is rendered extremely difficult.

It has been found that changes in the wavelength inside the said order of magnitude are associated with every change in energy of the transmitter tube. Consequently a keying method that would suggest itself can be expressed: keying signal=full energy, keying intermission=no energy, which method is readily applicable in connection with long waves, but is useful for short-wave work only when the operating means supply full energy also during the intermissions, in which instance the same must be destroyed by an additional element or means. This results in a considerable enlargement and an increase in cost of apparatus.

The same end may be attained in a simple manner by detuned keying, in the presence of perfectly constant, or substantially perfectly constant energy. In the case of short waves, this method is especially suited for the reason that the wave variation has to be only very small in order to furnish a change in frequency sufficient for the reception of the keyed signals.

In telegraphic work on short waves it has been discovered that undamped telegraphic signals, to be sure, can be transmitted to very great distances, but that it is difficult to locate the transmitting station in heterodyne reception, or to re-locate it after it has been lost on account of fading or atmospherics. It is well known that this difficulty is not quite so great in the case of damped or modulated signal work.

However, in the case of modulated transmission, the question comes up again as to

what the most suitable keying method would be. The most correct method of keying is that from zero to full energy. However, since also in this case high wave-constancy is required, provisions must be made for an equalization of load to which reference was made above. If this complication is avoided, it is possible to work similarly as in the case of continuous wave work with detuned keying, except that here the changes in the waves must be incomparably larger than with continuous wave transmission. The transmitter requires a by far larger place in the frequency scale.

Now, the present invention discloses a new keying method adapted to solve the problem. According to the invention, the modulation of keying signals and keying intermissions is chosen differently in such a way that the keying signals possess a definite mode of modulation from one key signal to another, while the keying intermissions have another mode of modulation which is the same for each keying intermission.

The method may be practiced with either continuous waves or modulated waves. To realize differences in modulation, recourse could first be had to differences in the degree of modulation and for this purpose the keying signals are modulated at the same frequency as the intermissions, except that they are modulated much more markedly than the latter. Of course, a suitable plan is to make the degree of modulation of the keying intermissions as different as possible from that of the keying signals; for instance, the intermissions need not be modulated at all, that is to say, are sent undamped, while the keying signals are modulated to the fullest extent or the inverse plan could be followed.

Another method resides in that the modulation frequencies are chosen to be of different values, for instance, the key signals could be modulated at a frequency of 2000, while the intermissions could be modulated at a frequency of 200, or the intermissions could be modulated at some inaudible frequency.

The method hereinbefore indicated could be combined readily with the detuning of the wave-lengths. In this manner the best pos-

sible separation and differentiation between key dash, and space or keying intermission could be obtained.

In the following, a number of embodiments and arrangements adapted to the practicing of the method shall be described by way of example.

Fig. 1 shows an arrangement in which the degree of modulation is utilized.

Fig. 2 shows a diagram of connections whereby the signal or the intermission may be modulated.

Fig. 3 shows an arrangement whereby the frequency is modulated.

Fig. 1 shows an arrangement in which the degree of modulation of keying signals and keying intermissions is chosen so as to be of different value. The transmitting apparatus consists of a separately controlled tube transmitter comprising the oscillator tube S and the modulator tube H which operates upon the aerial A. The grid of the tube H is shut off from the coupling circuit by the aid of the blocking condenser B. The grid direct current flows through the choke coil D1, connecting points or terminal G, and resistance R1 to terminal K, and from there by way of choker D2 to the heated filament. Modulation is effected by way of the transformer Tr which is connected in parallel with relation to the resistance R1, and which consequently imparts to the grid of the main transmitter an additional alternating current component of the desired frequency. For the purpose of variation of the degree of modulation, a resistance R2 is inserted between Tr and R1 which may be short-circuited by the telegraph key T. It will be understood that when R2 is short-circuited the degree of modulation is naturally higher than when the key is open. Fig. 2 shows the direct current path and GK of the grid in the case where the keying signals are non-modulated and the keying intermissions modulated, or vice versa. The key is here disposed in parallel with reference to resistance R1, and therefore parallel to the modulating transformer Tr. By closing the key, modulation ceases. According to whether the key is arranged to operate as a working or as a back contact, either the signals or the spaces will be modulated. Fig. 3 shows an arrangement which makes it possible to choose the modulation frequency of keying signals and intermissions of different frequencies either of radio or audio frequencies. The grid direct current flows here from point G through the series-connected resistances R1 and R2. In parallel relation to R1 is a transformer Tr1, and in parallel to R2 a transformer Tr2, transformer Tr1 serving to transfer frequency N1 and Tr2 to transfer frequency N2. By means of key T provided with a working and a back contact, alternately the one or the other key instrument is shorted and ren-

dered inoperative. Hence, according to the mode of connection it is possible to use either the one or the other frequency for the signals or for the spaces.

Having fully described my invention, 70 what I claim is:—

1. In a transmitting system, a source of high frequency oscillations having its output electrodes connected with a load circuit, a thermionic modulator tube, means for impressing oscillations from said high frequency source on to the input electrodes of said modulator tube, a source of oscillations having a frequency characteristic of the signal units, a source of oscillations having a frequency characteristic of the marking units, and means for conductively connecting said sources in series across the input electrodes of said modulator and for separately connecting either of said sources across the input electrodes of said modulator. 75 80 85

2. A system as claimed in claim 1 including inductances connected in series with said conductively connecting means.
